PUZZLE BOARD

Judy A. Cohen, Cincinnati, Ohio, assignor to Rainbow Crafts, Inc., a corporation of Delaware

Filed May 15, 1969, Ser. No. 17,165

Term of patent 14 years

Int. Cl. D21—01

U.S. Cl. D34—15

The figure is a plan view of a puzzle board, showing my new design. The puzzle is of conventional thickness with the back of the puzzle being conventional.

I claim:

The ornamental design for a puzzle board, substantially as shown and described.
